UNITED STATES PATENT OFFICE

GEORGE E. McLAUGHLIN, OF PEABODY, MASSACHUSETTS, ASSIGNOR TO THE TURNER TANNING MACHINERY COMPANY, OF PORTLAND, MAINE, A CORPORATION OF MAINE

MACHINE FOR OPERATING UPON HIDES, SKINS, AND LEATHER

Application filed June 28, 1928. Serial No. 288,918.

This invention relates to machines for operating upon hides, skins, leather and other similar pieces of work and is illustrated as embodied in a machine for fleshing hides and skins. It is to be understood, however, that the invention and various important features thereof may have other applications and uses.

In prior constructions such as the fleshing machine of United States Letters Patent No. 873,790, granted Dec. 17, 1907, upon application of Rood and Perkins, pieces of work were presented to a bladed cylinder by means of a single bed roll movable between work receiving and work presenting positions. Just as the bed roll was about to present the work to the bladed cylinder it pressed the work against a feed roll carried by boxes slidable vertically in the frame of the machine. While machines of this type are still in general use, it is clear that there is a definite limit to their capacity since the operator must wait for the work to be fed out of the machine before he can introduce a second piece. Moreover, while, in the use of such a machine the skilled worker is almost never in danger, although he works close to the bed roll and its cooperating feed roll, the inexperienced or careless worker may occasionally be injured by having a hand pinched between the two rolls as the bed roll is moving to work presenting position with respect to the bladed cylinder.

Objects of the present invention are to increase the capacity of leather working machines and to increase the safety factor so that even inexperienced or careless workers will run no substantial danger in operating such machines.

To these ends, and in accordance with an important feature of the invention, a plurality of bed rolls are provided in the illustrated machine so that the operator may position a fresh piece of work on a bed roll in inoperative position at a safe distance from a feed roll while another piece previously introduced and operatively positioned by movement of another bed roll from a similar work receiving position is being operated upon by a work treating instrumental-

ity, the result being that the idle time of the operator is lessened and the machine thereby increased in its productive capacity. Furthermore, since the wear on a plurality of bed rolls is divided between them, adjustment and replacement is less frequently required for the same quantity of work produced. Conveniently, the bed rolls are mounted upon a rotary member, which may be termed a turret, so that first one and then another bed roll is swung into work receiving position and subsequently into work presenting position during the rotation of the turret member. Preferably, and as shown, the turret is locked with a bed roll in work presenting position with respect to the work treating instrumentality. Since the turret member, in the illustrated construction, is pivoted for rotation about central points in arms which support the bed rolls it follows that the bed roll at any given time in position to receive work from the operator is spaced at a considerable distance from the place where work upon another bed roll is being operated upon. Hence, the operator is kept at a distance from the field of operations and is working under conditions in which danger to himself is reduced to a minimum. This will be the more readily appreciated when it is understood that rotation of the turret member is initiated by the operator through a convenient member such as a foot treadle.

In order to prevent displacement of the piece of work after it has been placed upon a bed roll while the latter is in work receiving position, means is provided for maintaining each bed roll with a given surface facing in an upward direction during movement of the bed roll to work presenting position. To accomplish this result the illustrated means referred to operates to turn the bed roll in a counterclockwise direction continuously and at the same rate as the rotating turret would normally reverse the upper and lower surfaces of the bed roll in each half turn of the turret.

In a turret construction like that illustrated in the drawings, each bed roll in turn comes into co-operative relation with a

feed or pinch roll. Hence, to permit rotation of the turret member always in the same direction and so that the bed roll may pass by the feed or pinch roll, the latter is mounted so as to move upwardly away from the path of the bed rolls. Preferably, and as shown, the feed roll is carried by two pivoted arms counterweighted to balance the greater part of the weight of the feed roll, which drops down when the bed roll or other supporting means is not there to support it. In order that a piece of work on the bed roll may not have to take the pressure incident to overcoming the inertia of the feed roll if the latter were lifted by the bed roll when it is coming into work presenting position, means is provided for lifting the bed roll, the illustrated means being controlled by the turret member. An advantage of this construction resides in the fact that too great a pressure between the bed roll and feed roll might damage the work, particularly in fleshing and unhairing operations in which the hides or skins which constitute the work are in a soft and more or less gelatinous condition.

It is a further important feature of the invention that means under the control of the turret is provided for moving the feed roll into, and holding it in, proper co-operative relation with respect to each bed roll in turn to cause effective feeding of the work irrespective of the size of the bed roll. This makes it possible to utilize a worn bed roll and a new bed roll in the same turret member. In other words, it is not necessary to replace both worn bed rolls at the same time if there is still considerable service to be gotten from one of them. In that case the completely worn bed roll may be replaced by a new bed roll properly adjusted in the turret member, whereupon the turret controlled means already referred to will automatically adjust the feed roll alternately to the worn bed roll and to the new bed roll. In the illustrated construction, the turret controlled means for controlling the position of the feed roll are found in cam projections or bosses on boxes in which the bed rolls are mounted on the turret arms. Since the boxes are adjusted on the turret to position the bed rolls with respect to the work operating instrumentality, it follows that the bed rolls control the positions of the cam projections and, therefore, the position of the feed roll. These cam projections or bosses co-operate with similar cam projections or bosses on levers which operate the supports for the feed roll to move the latter into proper co-operative relation to each bed roll in turn.

Since each bed roll is pressed yieldingly toward the work operating instrumentality to accommodate variations in the thickness of the work and since adjusting movement of

the bed roll for the purpose just stated is accompanied by movement of the boxes in which the bed roll is mounted, it follows that the cam projections or bosses on the boxes change their positions in accordance with variations in the thickness of the work. Hence the feed roll controlled by the cam projections or bosses is automatically adjusted to the thickness of the work, approaching the bed roll more closely for engagement with thin pieces of work and receding somewhat for thicker pieces of work or for thick portions of the same piece of work, so as not to injure the latter by too severe feeding pressure.

In order that the rate at which the work passes the work treating instrumentality may be varied to suit varying conditions, improved means is provided under the control of the operator to vary the speed of the feeding means for the work while the speed of the treating instrumentality remains unchanged. As shown, this means comprises a set of gears of various sizes and a manually controllable lever for selecting one of the gears for introduction into the gearing for driving the feed roll.

Other features of the invention relate to constructions and arrangements by which the bed rolls may be adjusted with relation to the work treating instrumentality, illustrated as a bladed cylinder, so as to compensate for wear of the surfaces of the bed rolls, other means being provided for adjusting the tension of springs which back the bed rolls and the adjustment of the spring tension in each case being separate and distinct from the adjustment of the normal position of the bed roll with respect to the bladed cylinder.

These and other features of the invention and novel combinations of parts will now be described in detail by reference to the accompanying drawings and then pointed out more particularly in the appended claims.

In the drawings,

Fig. 1 is a view in end elevation of a fleshing machine embodying the invention;

Fig. 2 is a plan view from above of the machine shown in Fig. 1;

Fig. 3 is a front elevation of the machine;

Fig. 4 is a detail illustrating diagrammatically adjustments of the bed rolls with respect to the bladed cylinder and of the feed roll and bladed cylinder with respect to the bed rolls;

Fig. 5 is an end view, partly in section, illustrating the bed rolls, the bladed cylinder, and the feed roll, with a bed roll approaching work presenting position;

Fig. 6 is a view similar to Fig. 5 with one of the bed rolls in co-operative relation to the bladed cylinder and the feed roll, this view being a section along the line VI—VI of Fig. 2;

Fig. 7 is a view similar to Figs. 5 and 6 showing a bed roll moving away from the bladed cylinder and the feed roll and another bed roll approaching the bladed cylinder;

Figs. 8, 9 and 10 are similar to Figs. 5, 6 and 7, respectively, the only difference being that a worn bed roll occupies the positions of the new bed roll of Figs. 5, 6 and 7;

Fig. 11 illustrates diagrammatically the adjustment of the bladed cylinder with respect to the bed rolls;

Fig. 12 is a detail view of one of the turret arms illustrating the adjusting means for the bed rolls and also the adjusting means for varying the tension of the springs which back the bed rolls, the view being a section taken along the line XII—XII of Fig. 2; and

Fig. 13 is a detail view of the bed roll driving means taken along the line XIII—XIII of Fig. 3.

In the illustrated machine which is designed especially for fleshing operations upon hides and skins, there is provided as a work treating instrumentality a bladed cylinder 20 supported upon a shaft 22 (Figs. 1, 2 and 11) the ends of which are journaled in boxes of similar construction and arrangement. One of these boxes is shown at 24 (Fig. 11) supported for adjustment upon a stationary frame member 26 having a horizontal bracket 28 slotted, as at 30, to receive slidably a securing bolt 32 adapted to secure the box 24 in adjusted position. For securing adjustment of the box 24, the bolt 32 is first loosened and then a screw threaded member 34 is properly manipulated to adjust the box 24 after which the bolt 32 is again tightened to hold the box in its new position, the adjustment of the boxes being for the purpose of positioning the cylinder 20 in proper relation to work presenting means which will now be described.

The work presenting means referred to in the preceding paragraph comprises a plurality of rubber-covered bed rolls, two bed rolls, 40 and 42, being the number employed in the illustrated construction. Since the machine is specially constructed so as to make it possible to utilize a worn bed roll and at the same time a new bed roll, the parts are shown adjusted for a worn bed roll 40 and a new bed roll 42, both bed rolls being carried in a turret member comprising turret arms 44, 46 (Figs. 2 and 3). The arms 44, 46 are each carried by, and fixedly secured to, a shaft 48 mounted in bearings 50 at each end of the machine, each turret arm being mounted at its central point upon its corresponding shaft so that the turret arms may be of equal length, and rotatable upon rotation of the shaft 48. Upon inspection of Fig. 2, it will be observed that the bed rolls 40, 42 are carried at their op-

posite ends by boxes 52 mounted in opposite ends of each of the turret arms 44 and 46. Preferably, and as shown, each bed roll 40, 42 comprises a shaft 54, 55, respectively, each end portion of which rests in one of the boxes 52 and has an extension beyond the box for a weighted member 56, one at each end of each of the shafts 54, 55, the purpose of which will hereinafter be described. It will be clear from an inspection of Figs. 2 to 10, inclusive, that the turret member, comprising the turret arms 44, 46, is rotatable about the center of the shafts 48 to present the bed rolls 40, 42 successively in work receiving and work presenting positions. When the roll 40 is in work receiving position, as in Figs. 2, 3 and 6, the operator may place a piece of work upon this bed roll with perfect safety, since it is at a considerable distance from the bladed cylinder 20 and from a feed roll 60, the latter being sometimes referred to as a pinch roll, since it co-operates with the bed rolls in turn to grip work in work presenting position with respect to the bladed cylinder. After the work has been operated upon through the co-operation of the bladed cylinder 20 and the bed roll 42 in Figs. 2, 3 and 6, the operator depresses a treadle 62 whereupon the turret member is rotated to bring the bed roll 42 to work receiving position, at the same time carrying the bed roll 40 to work presenting position, and this operation is repeated as often as the operator gets a fresh piece of work positioned upon the bed roll in work receiving position.

As already stated, each of the shafts 54, 55, carries at its opposite ends weighted members 56 so constructed and arranged that the center of gravity is considerably below the axis of the shaft. Carried by an arm 70 (Figs. 1, 2, 3 and 6) projecting upwardly from each weighted member 56 is a spring pressed ratchet pawl 72 adapted to engage selectively with teeth of a ratchet wheel 74 pinned to the adjacent end of the shaft 54 or 55. The spring pressure back of the pawls 72 is sufficient to cause the shaft 54 or 55 to turn with the weighted members 56 at each end of the shaft. Hence, as the turret arms 44, 46 are revolved, the weighted members 56 operate to rotate the bed roll in a counterclockwise direction continuously and at the same rate as the rotating turret would normally reverse the upper and lower surfaces of the bed roll in each half turn of the turret. Thus the members 56 operate to keep the bed rolls 40, 42 always with the same portion of their cylindrical surfaces facing upwardly so that the line of the hide or skin positioned by the operator to lie along the top of the bed roll while the latter is in work receiving position will remain on top during travel of a bed roll inwardly to work presenting

position. Were it not for this provision there would be danger of the work being displaced or even of its being discharged from the bed roll since the latter, supported by a rotatable turret, would normally have its upper and lower surfaces reversed in its movement through 180° from work receiving position to work presenting position.

While the bed roll 40 or 42 is arriving at work presenting position with respect to the bladed cylinder 20, a long-toothed gear 78, (Figs. 2, 3 and 13) fixedly secured to each bed roll, comes into mesh with a similar gear 80 mounted upon shaft 82 of the feed roll 60. Since the feed roll 60 is driven continuously and positively during the operation of the machine, it is preferable to have the gear 80 yieldingly mounted upon the shaft 82 so as gradually to overcome the inertia of the bed roll which starts from rest. For this reason the gear 80 has attached thereto a lug 81 which is normally held by a spring 84 against a face 85 on a collar 87 fixed to the shaft 82. Upon meshing of the gears 78 and 80 the spring yields to permit the lug 81 to engage an opposite face 89 on the collar 87 by which the gear 80 is driven positively. In the meantime the spring 84 has operated to overcome the inertia of the bed roll. Furthermore, the parts just described serve as a lost motion connection between the bed and feed rolls to insure that the bed roll does not start positively in rotation until just before the bed roll presents the work to the cylinder. Upon meshing of the gears 78 and 80 the bed roll 40 or 42, as the case may be, begins to rotate in the direction of the arrow (Figs. 2, 6 and 13) to feed the work past the bladed cylinder 20 and in a direction toward the operator's position at the front of the machine, the feeding movement of the bed roll beginning just an instant before the work is pressed against the bladed cylinder, to insure that the work is gripped between the bed roll and its co-operating feed roll 60 before contact with the bladed cylinder which otherwise might jerk the piece of work from the bed roll. As soon as the gears 78 and 80 mesh with each other and the bed roll begins to rotate the pawl 72 ratchets over the teeth of its ratchet wheel 74, thereby permitting the weighted members 56 at each end of the bed roll to remain in depending position.

In order to permit adjustment of each bed roll independently of the other so that they may co-operate properly with the bladed cylinder and with the feed roll when in work presenting position, each of the turret arms 44 and 46 is provided with means for accomplishing individual adjustment of the boxes 52 which afford journal bearings for the shafts 54 and 55 of the bed rolls. Upon reference to Fig. 12 of the drawings it will be observed that each box 52 has extensions 90

screw threaded to receive screw threaded bolts 92, the other ends of which are movably received in smooth-surfaced perforations 94 in end plates 96 bolted to the adjacent end of the arm 44 or 46. Upon each bolt 92 is a set nut 98 for holding the bolt in adjusted position on the box 52. Between each box 52 and an associated plate 100 is a spring 102 for yieldingly backing the box 52 so that the bed roll, carried at its ends by two boxes 52 in corresponding ends of the turret arms 44 and 46, may yield and thereby accommodate variations in the thickness of the work passing between the bed roll and the bladed cylinder. For adjusting the tension of each spring 102 independently of the position of its associated box 52, the plate 100 has projections 104 adapted to receive the screw threaded ends of bolts 106, the head ends of which pass movably through perforations in projections 108 extending from the body portion 110 of the arm 44 or 46. Proper manipulation of the bolts 106 will serve to adjust the plate 100 in a manner that will be readily understood.

When a bed roll and bladed cylinder are new and, therefore, of full size they are positioned in the co-operative relationship shown in full lines in Fig. 4 and in this position of the bed roll its center will describe a circle, during rotation of the turret arms 44, 46, whose center is in the center line of the shafts 48 (Fig. 4). As the bed roll wears away it must be adjusted so that its axis is beyond the circle mentioned, so as to keep it at the proper spacing with respect to the cylinder 20. In this same Fig. 4, it will be observed that the cylinder 20 as it wears away will be adjusted to the right in said figure so as to keep the line of contact between the bed rolls and the cylinder always in the same vertical plane and therefore in proper relation to the feed rolls 60. In this figure, the bladed cylinder 20 is shown in full lines indicating a new full sized cylinder, it being also shown in dotted lines 20a to indicate the position of a much worn cylinder of relatively small size. Fig. 4 also shows the bed roll 42 in full lines as a new normal-sized bed roll and, in dotted lines 42a, the same bed roll after it has become worn and much reduced in size, adjustment having been made from time to time to keep the worn bed roll in proper spacing with respect to the bladed cylinder. Furthermore, in this same figure the feed roll 60, with its fluted surface, is shown in full lines in the position it occupies when co-operating with a new full-sized bed roll such as that at 42, while in dotted lines the same feed roll 60 is shown adjusted to the worn bed roll, shown in dotted lines at 42a. In passing, it may be stated that adjustment of the feed roll 60 to bed rolls of different

and varying sizes is made automatically, as will hereinafter be described.

For lifting the feed roll 60 as one of the bed rolls is coming into co-operative relation to the cylinder 20, and for controlling the position of the feed roll with respect to the incoming bed roll, the turret arms 44, 46 are each provided with lifting projections 116, 118 upon opposite sides thereof each 5 projection carrying a cam roll 120 each adapted to enter alternately a cam slot 122 in a lifting lever 124, there being a lever 124 at each end of the machine pivoted at 126 upon a stationary standard 128. Hence 10 a description of one lever 124 and the parts connected to and operated thereby will apply equally to the other lever. At 130 the lifting lever 124 is provided with a roll adapted to travel in a slot 132 in a U-shaped 15 member 134 pivoted about the axis of a roll 136 which is movable along a slot or guideway 138 in the frame post 140. Pivoted upon the axis of the roll 136 is a link member 142 which passes slidably through 20 the back wall of the guideway 138, a spring 144 being interposed between said back wall and the adjacent edge of the member 134, the construction and arrangement being such 25 that the U-shaped member 134 may yield 30 under pressure of a lever now to be described. Pivoted at 150 upon the upper arm of the U-shaped member 134 is a lever 152, the lower end of which carries a roll 154 which is movable in a vertical direction 35 within a slot 156 of a guideway member 158 rigid with the frame post 140. At its upper end the lever 152 is provided with a roll 160 movable in a slot 162 obliquely arranged 40 in a supporting arm 164 pivoted at 166 to the upper end of the frame post 140. At one end the arm 164 carries a box 168 which provides a journal bearing for one end of the shaft 82 of the feed roll 60. At its other end each supporting arm 164 carries a 45 weight 170 (Figs. 1 and 2) which may be adjusted upon the arm and secured in fixed position, the purpose of the weights 170 being to counterbalance the greater part of the weight of the feed roll 60 carried at the 50 forward end of the arms 164.

As the turret arms 44, 46 swing about the centers of the shafts 48 to bring one of the bed rolls 40, 42 into cooperative relation with respect to the bladed cylinder 20, one 55 of the rolls 120 on the lifting projection 116, 118 engages within the slot 122 of the lifting lever 124 (Fig. 5). Continued movement of the turret in the same direction lifts the lifting levers 124 which, through the 60 U-shaped levers 134, move the levers 152 in an upward direction thereby lifting the forward ends of the feed roll supporting levers 164. In this way the feed roll 60 is lifted by force applied indirectly by the turret. 65 The feed roll is not lifted by the bed roll

pressing the work against the feed roll, as in certain prior constructions wherein excessive pressure on the work caused by overcoming the inertia of the feed roll sometimes results in damage to the work. At 70 the same time that the levers 152 become operative to lift the feed roll supporting levers 164, the said levers 152 also operate to adjust the feed roll 60 to the bed roll coming into co-operative relation with respect to the bladed cylinder, as will presently be described. 75

After the piece of work has been operated upon by the bladed cylinder, the operator depresses the treadle 62 and thereby initiates 80 another rotative movement of the turret so that the bed rolls may move from work receiving to work presenting positions and vice versa. In order that the bed roll which has been presenting the work to the bladed cylinder 20 may move away from that position it is necessary that the feed roll be carried upwardly out of the way, this movement being indicated in Fig. 7 of the drawings. Here, again, it is desirable that the feed roll should be moved upwardly by power supplied by the turret, and not through pressure of the rubber covered bed roll against the rotating brass roll 60 with its fluted surface. Hence, the lifting levers 90 124 are swung upwardly by the rolls 120 in the further movement of the turret, thereby lifting the U-shaped levers 134 and the levers 152 connected thereto. Fig 7 shows a roll 120 as it is about to escape from the slot 122 in the lifting lever 124. At this time, the bed roll has passed beyond the feed roll 60. Hence, when the rolls 120 leave the lifting levers 124, the latter together with their connected levers leading 100 up to the feed roll supporting levers 164 and the feed roll 60 will all drop through the force of gravity, so that these parts may be picked up again as the next bed roll is approaching work presenting position with 105 respect to the bladed cylinder 20. To prevent unnecessary jarring of the parts as they drop, there is provided a spring supported abutment member 173 positioned in the path of each of the lifting levers 124 110 115 so that the latter contact with and depress the abutments yieldingly in the downward movement of the lifting levers and the parts supported thereby including the feed roll 60 until the abutments reach stationary positions with springs 175 fully compressed. 120

As shown most clearly in Figs. 5 to 10, inclusive, of the drawings the lever 152, and this applies to lever 152 at the other end of the machine, is provided with a boss 169 adapted to be engaged by a boss 171 on the surface of each of the two boxes 52 at that end of the machine as the latter come alternately into alignment with a line joining the centers of the bladed cylinder 130

20 and the shaft 48. In this way the lever 152 is caused to swing about its pivot point 154, against the force of the spring 144, to pull the forward end of the arm 164 5 downwardly, thus holding the feed roll 60 in predetermined relation with respect to the bed roll 40 or 42, except for the yielding arrangement provided by springs 174 which back the feed roll 60 in a manner 10 which will hereinafter be described. This movement of the lever 152 takes place to a very slight extent where a new full-sized bed roll is being used. As the bed roll 40 or 42 wears away it is adjusted toward the 15 left, that is, toward the bladed cylinder 20 to keep in proper co-operative relation thereto and with each slight adjustment the boss 171 on each box 52 causes a greater movement of the lever 152 by contact with the 20 boss 169 on the lever, thereby causing the feed roll 60, by the action of the roll 160 in the cam slot 162, to move downwardly a greater distance to come into co-operative 25 relation with respect to the worn bed roll. An extreme case of this is illustrated in Fig. 9 of the drawings, in which the well-worn bed roll 40 is shown in work presenting position with respect to the bladed cylinder 20. Since the worn bed roll 40 and 30 its journal boxes 52 have been adjusted in the manner and for the reasons indicated in Fig. 4, the boss 171 is positioned much further to the left in Fig. 9 than is the boss 171 on the corresponding box of bed roll 42 in Fig. 6, for instance. This position of the boss 171 in Fig. 9 causes the lever 152 to have its upper end moved a considerable distance to the left, in which case the roll 160 at the upper end of the lever 152 35 is caused to ride the full distance along the slot 162, thereby causing maximum depression of the lever 164. In this way the feed roll 60 is automatically adjusted with respect to the bed roll as each bed roll 40 and 42 come alternately into work presenting 40 position with respect to the bladed cylinder 20. In the described movement of the lever 152 it turns about its lower end as a pivot, the pivot being in the roll 154 which 45 is located within the slot 156 of the stationary guideway 158. Hence, the described movement of the lever 152 shifts the U-shaped member 134 to the left in Fig. 9 against the tension of the spring 144. It 50 is clear then that spring 144 tends to keep the levers 134 and 152 over to the extreme right as their initial position of rest from which they may be displaced by the boss 171 coming in contact with the boss 169 55 on the lever 152. Since the lever 152 connects the U-shaped lever 134 rigidly (though adjustably) with the lever 164, it follows that the lever 124 is also held rigidly with respect to the lever 164 since the lever 124 60 has a roll at 130 confined within the slot 65

132 of the lever 134. Hence, the feed roll is held locked with respect to the bed roll on the turret by reason of the engagement of the roll 120 within the slot 122 of the lever 124, except as the feed roll may yield 70 against the springs 174. For locking the turret with a bed roll in operative position, the means for rotating the shafts 48 through each half revolution comprises a stop block 183 which operates to hold the turret arms 75 locked with the bed rolls in work receiving and work presenting positions respectively, as will now be described.

Upon reference to Figs. 1, 2 and 3, the driving means for the shafts 48 are seen 80 to comprise a sprocket wheel 190 fastened to each shaft and about which passes a sprocket chain 192 which engages at its other end with a second sprocket 194 fixed to shaft 196. This shaft 196 is driven by a 85 gear 198 (Fig. 2) which is constantly in mesh with a pinion 200 normally loose on a shaft 202 arranged to be driven continuously from any desired source of power through connections to a power pulley 204 fixed upon the end of the shaft 202. Pinion 200 is fixed to a wheel 206 which is also loose on the shaft but which is adapted to be clutched thereto through the operation of a cone clutch of well-known construction comprising a cone member 208 (Fig. 2). Carried by a shaft 209 which operates the clutch is a stop lever 211 which at its upper end drops into a slot 213 in the stop block 183, the construction and arrangement being such 95 that as the clutch is thrown in the stop lever 211 is retracted to free the stop block. The stop block is provided with a cam surface 215 adapted to hold the lever 211 in position to maintain the clutch lever in operative or 100 clutching position. When the stop lever 211 engages in the slot 213 it causes the turret to stop with the bed roll 40 or 42 in operative relation to the cylinder 20 and maintains it locked in such relation. Hence, at 105 each turn of the wheel 206 the stop lever 211 drops into the slot 213 and holds the stop block 183 in locked position. Since all of the 110 connections between the stop block 183 on shaft 196 and the sprockets 190 on the shafts 48 are positive, it is clear that the turret arms are held in locked position also with the bed rolls 40, 42 one in work receiving and the other in work presenting position.

Upon inspection of Fig. 6 of the drawings, it will be observed that the box 168 for supporting one end of the feed roll 60 is slidable vertically within a guideway 172, a spring 174 being interposed between the box 168 and a collar 176 adjustably mounted on a block 178 at the upper end of the guideway 172. As shown, the collar 176 is secured to an adjustable member 180 which is screw threaded within the block 178 so as to be adjustable with respect thereto to 115 120 125 130

5 tension the spring 174. Passing through the member 180 is a rod 182, the lower end of which is secured to the box 168 to limit the movement of the box under pressure of the spring 174, it being understood, however, that the box 168 may move upwardly within the guideway 172, the spring 174 yielding to permit this movement of the box 168 whereby the feed roll 60 supported by the 10 two similarly arranged boxes 168 at the forward ends of lever 164 may accommodate variations in the thickness of the work passing between it and the bed roll 40 or 42.

15 For driving the feed roll 60 there is provided a sprocket wheel 220 (Fig. 2) fixedly secured to the continuously driven shaft 202. Passing around this sprocket wheel is a chain 222 (Figs. 1 and 2) which also engages and drives a sprocket wheel 224 on a countershaft 226. At the other end of the countershaft is a pinion 228 constantly in mesh with a pinion 230 (Fig. 1). This pinion 230 is adapted to be shifted longitudinally of pinion 228 to come into 20 mesh selectively with one of the three gears 232, 234, 236 fast on a shaft 238, the purpose being to vary the speed of the shaft 238 by means under the control of the operator, the said means including the pinion 230 and a handle lever 240 by which the pinion 230 may be shifted to mesh selectively with the gears 232, 234, 236. Upon inspection of 25 Figs. 1 and 2 it will be observed that the lever 240 may be locked in its adjusted position by means of a spring-pressed locking pin 242 receivable in any one of three locking recesses 244 (Fig. 2). Secured to the shaft 238 is a sprocket wheel 250 around which passes a chain 252 engaged also with 30 a sprocket 254 secured to the shaft 82 of the feed roll 60 for driving the latter continuously while the machine is in operation. The bladed cylinder 20 is also driven continuously in the illustrated construction by 35 means of a power pulley 260 secured upon the shaft 22 of the cylinder at the right-hand end thereof in Fig. 2 of the drawings.

40 In operating the illustrated machine a hide or skin is placed upon the bed roll 40 (Fig. 2) and the machine started in operation by depressing the treadle 62. Depression of the treadle initiates a half revolution of the turret comprising turret arms 44, 46 during which the bed roll 40 is moved from 45 work receiving position (Figs. 2 and 6) to work presenting position (Fig. 7). During rotation of the turret, the bed roll 40 is turned by its weighted members 56 so that the roll maintains the same portion of its 50 cylindrical surface facing in an upward direction, thereby retaining in place the hide or skin W which is folded over the roll with substantially equal portions depending from each side of the roll. Finally the bed roll 55 40 swings into place (Fig. 9) to present the

work to the bladed cylinder 20. While the turret is moving in the manner described, the operator picks up another piece of work and promptly places it upon the bed roll 40 as the latter reaches work receiving position 70 indicated in Fig. 9. He then reaches over bed roll 42 (which is stationary at this time) and the work thereon and grasps the near portion of the piece of work which is being fed out toward him on the bed roll 40 while 75 the cylinder 20 is operating on the portion of the work between it and the bed roll. Since each piece of work is folded over a bed roll with substantially equal parts depending on each side of the bed roll, the 80 cylinder operates upon approximately one half of each piece of work at each depression of the treadle. As soon as the work is free from the cylinder 20 the operator again depresses the treadle 62 whereby the bed roll 85 42 travels toward work presenting position with respect to the cylinder 20 at the same time that the bed roll 40 is traveling toward work receiving position. When it gets in this position (Fig. 6) the operator places 90 upon this bed roll the piece of work which he has just removed from it, in the meantime having changed it around or end for end so as to have the untreated portion facing toward the bladed cylinder. He then 95 reaches for the piece of work on the bed roll 42 and supports portions of that piece of work while it is being fed out toward him from between the bed roll 42 and the cylinder 20. As soon as this piece of work is 100 free he again depresses the treadle 62 following which the bed roll 40 moves toward the bladed cylinder 20 with the half treated piece of work thereon. When the bed roll 42 reaches work receiving position, indicated 105 in Fig. 9, he reverses the piece of work and hangs it over the bed roll 42 and again depresses the treadle. When the bed roll 40 reaches the bladed cylinder 20 treatment of the piece of work on this bed roll is soon 110 completed and it may be allowed to drop upon a conveyor (not shown). Ordinarily, however, the operator will grasp it as it is being fed out toward him and when free will place it upon a horse near at hand, then 115 seizing a fresh piece of work, he places it upon the bed roll 40 as the latter reaches work receiving position. These operations are repeated indefinitely during the work hours. It is to be noted that each piece of work is operated upon twice while supported on the same bed roll, thereby insuring more 120 certainly equal treatment of both halves of each piece of work.

Having described my invention, what I 125 claim as new and desire to secure by Letters Patent of the United States is:

1. In a machine for operating upon hides, skins, leather and other similar pieces of work, an instrumentality for operating on 130

the work, and a plurality of bed rolls for supporting pieces of work and movable in succession to present the pieces of work in turn to the operating instrumentality, means 5 for driving the work presenting bed roll during co-operation thereof with said instrumentality in effecting treatment of the work, and means for supporting the bed rolls in spaced relation with respect to each 10 other and their driving means to permit positioning of work on one bed roll while another bed roll is in work presenting position with respect to said instrumentality.

2. In a machine for operating upon hides, 15 skins, leather and other similar pieces of work, an instrumentality for operating on the work, and a plurality of bed rolls for supporting pieces of work and movable in succession along a circular path to present 20 the pieces of work in turn to the operating instrumentality, means for driving the work presenting bed roll during co-operation thereof with said instrumentality in effecting treatment of the work, and means for 25 supporting the bed rolls in spaced relation with respect to each other and their driving means to permit positioning of work on one bed roll while another bed roll is in work presenting position with respect to 30 said instrumentality.

3. In a machine for operating upon hides, 35 skins, leather and other similar pieces of work, an instrumentality for operating on the work, a turret member, and a plurality of bed rolls carried by the turret member and movable in succession to work receiving position and subsequently to work presenting position for co-operation with the operating instrumentality, and means for 40 rotating each bed roll while in work presenting position, the turret being stationary during such rotation of the bed roll.

4. In a machine for operating on hides, 45 skins, leather and similar pieces of work, an instrumentality for operating on the work, and a plurality of bed rolls each movable bodily between a work receiving position and a work presenting position with respect to the working instrumentality, each bed roll being rotatable while in work 50 presenting position to present successive portions of work supported thereon for the operation of the operating instrumentality, and one bed roll being stationary in work receiving position while another bed roll is presenting the work to the operating instrumentality.

5. In a machine for operating on hides, 60 skins, leather and similar pieces of work, an instrumentality for operating on the work, a plurality of work supports, a turret for carrying the work supports between work receiving and work presenting positions with respect to the operating instrumentality, and means for driving each work 65

support in turn while it is in work presenting position, each work support being stationary while in work receiving position.

6. In a machine for operating upon hides, 70 skins, leather and other similar pieces of work, an instrumentality for operating on the work, a turret member, a plurality of bed rolls carried by the turret member and arranged to be presented in succession for co-operation with the operating instrumentality, each bed roll being adapted to have a piece of work looped thereover and to carry it from work receiving position to a work presenting position with respect to 75 said instrumentality, and means under the control of the operator for determining the time of rotation of the turret member.

7. In a machine for operating upon hides, 80 skins, leather and other similar pieces of work, an instrumentality for operating on the work, a turret member, a plurality of bed rolls carried by the turret member and arranged to be presented in succession for co-operation with the operating instrumentality during rotation of the turret member, 85 and means for locking the turret member with one bed roll in co-operative relation with respect to the operating instrumentality and another bed roll in work receiving position.

8. In a machine for operating on hides, 90 skins, leather and similar pieces of work, an instrumentality for operating on the work, a plurality of work supports, a turret for carrying the work supports to present each work support in turn in co-operative relation with respect to the operating instrumentality, and means for locking the turret with one work support in the recited 100 co-operative relation and with another work support in a work receiving position.

9. In a machine for operating upon hides, 105 skins, leather and other similar pieces of work, an instrumentality for operating on the work, a turret member rotatable about 110 an axis parallel to the operating instrumentality, a plurality of bed rolls carried by the turret member and arranged to be presented in succession during rotation of the turret member for co-operation with the operating instrumentality, power means for rotating the turret member, means operative to lock the turret member with one of the bed rolls in co-operative relation to the operating instrumentality, and means under the 115 control of the operator for unlocking the turret member.

10. In a machine for operating upon hides, 120 skins, leather and other similar pieces of work, an instrumentality for operating on the work, a turret member rotatable about 125 an axis parallel to the operating instrumentality, a plurality of bed rolls carried by the turret member and arranged to be presented in succession during rotation of the turret 130

member for co-operation with the operating instrumentality, power means for rotating the turret member, said power means being operative also to lock the turret member 5 with one of the bed rolls in co-operative relation to the operating instrumentality, and means under the control of the operator for initiating operation of the power means and for unlocking the turret member 10 simultaneously with the initiation of the rotation of the turret member.

11. In a machine for operating upon hides, skins, leather and other similar pieces of work, an instrumentality for operating on 15 the work, a work feeding member mounted adjacent to the operating instrumentality, and a plurality of bed rolls movable in succession from a position of spaced relation with respect to the operating instrumentality and the work feeding member into co-operative relation thereto to secure treatment of successive pieces of work.

12. In a machine for operating upon hides, skins, leather and other similar pieces of work, an instrumentality for operating on 25 the work, a work feeding member mounted adjacent to the operating instrumentality, a plurality of bed rolls for supporting pieces of work, and a turret member carrying the bed rolls and rotatable to bring the bed rolls in succession from a work receiving position into co-operative relation with respect to the operating instrumentality and the work feeding member.

13. In a machine for operating on hides, skins, leather and similar pieces of work, an instrumentality for operating on the work, a plurality of bed rolls for presenting pieces of work successively to the operating 30 instrumentality, a feed roll for co-operation with each bed roll in turn for feeding the work past the operating instrumentality, and means controlled by the position of each bed roll for controlling the position of the feed roll with relation to the bed roll.

14. In a machine for operating on hides, skins, leather and similar pieces of work, an instrumentality for operating on the work, a plurality of bed rolls for presenting pieces 35 of work successively to the operating instrumentality, a feed roll for co-operation with each bed roll in turn for feeding the work past the operating instrumentality, and means for automatically adjusting the feed roll to each bed roll as the latter comes into co-operative relation with respect to the feed roll and the operating instrumentality.

15. In a machine for operating upon hides, skins, leather and other similar pieces of work, an instrumentality for operating on 40 the work, a movably mounted feeding member adjacent to the operating instrumentality, a plurality of bed rolls for supporting pieces of work, a turret member carrying the bed rolls and movable to present the bed

rolls in succession in co-operative relation with respect to the operating instrumentality and the feeding member, and turret controlled means for adjusting the feeding member with respect to each bed roll in 70 turn.

16. In a machine for operating upon hides, skins, leather and other similar pieces of work, an instrumentality for operating on the work, a movably mounted feeding 75 member adjacent to the operating instrumentality, a plurality of bed rolls for supporting pieces of work, a turret member carrying the bed rolls and movable to present the bed rolls in succession in co-operative relation with respect to the operating instrumentality and the feeding member, and means associated with each bed roll operative to control the position of the feeding member with respect to each bed roll in 80 turn as the latter is coming into co-operative relation with respect to the operating instrumentality.

17. In a machine for operating upon 85 hides, skins, leather and other similar pieces of work, an instrumentality for operating on the work, a movably mounted feeding member adjacent to the operating instrumentality, a plurality of bed rolls for supporting pieces of work, a turret member 90 carrying the bed rolls and movable to present the bed rolls in succession in co-operative relation with respect to the operating instrumentality and the feeding member, boxes for supporting each bed roll at its 95 ends in the turret member, said boxes being adjustable so that the bed roll may be positioned in predetermined relation to the operating instrumentality, and cam projections on the boxes for causing movement of the feeding member into proper co-operative relation with respect to the bed roll as the latter is coming into co-operative relation with respect to the operating instrumentality. 100

18. In a machine for operating upon 105 hides, skins, leather and other similar pieces of work, an instrumentality for operating on the work, a movably mounted feeding member adjacent to the operating instrumentality, a plurality of bed rolls for supporting pieces of work, a turret member carrying the bed rolls and movable to present the bed rolls in succession in co-operative 110 relation with respect to the operating instrumentality and the feeding member, levers for supporting the feeding member, boxes for supporting each bed roll at its 115 ends in the turret member, said boxes being adjustable so that the bed roll may be positioned in predetermined relation to the operating instrumentality, and cam projections on the boxes for controlling the operation of the levers to cause movement of the feeding member into proper co-operative 120 relation with respect to the bed roll. 125

19. In a machine for operating upon 130 hides, skins, leather and other similar pieces of work, an instrumentality for operating on the work, a movably mounted feeding member adjacent to the operating instrumentality, a plurality of bed rolls for supporting pieces of work, a turret member carrying the bed rolls and movable to present the bed

relation with respect to the bed roll as the latter is coming into co-operative relation with respect to the operating instrumentality.

- 5 19. In a machine for operating upon hides, skins, leather and other similar pieces of work, an instrumentality for operating on the work, a feeding member movably mounted adjacent to the operating instrumentality, a plurality of bed rolls for supporting pieces of work, a turret member carrying the bed rolls and movable to present the bed rolls in succession in co-operative relation with respect to the operating instrumentality and the feeding member, boxes for supporting the ends of each bed roll in the turret member, means for yieldingly backing the boxes so that the bed roll may yield with respect to the operating instrumentality to accommodate variations in thickness of the work, and means controlled by the boxes for determining the position of the feeding member with respect to the bed roll so that the feeding member will be automatically adjusted in accordance with variations in the thickness of the work between the bed roll and the operating instrumentality.
- 10 20. In a machine for operating upon hides, skins, leather and other similar pieces of work, an instrumentality for operating on the work, a feeding member movably mounted adjacent to the operating instrumentality, a plurality of bed rolls for supporting pieces of work, a turret member carrying the bed rolls and movable to present the bed rolls in succession in co-operative relation with respect to the operating instrumentality and the feeding member, each bed roll being yieldingly adjustable to accommodate variations in the thickness of the piece of work between it and the operating instrumentality, and means for automatically adjusting the feeding member with respect to the bed roll as the latter moves in accommodating itself to said variations in the work.

- 15 21. In a machine for operating upon hides, skins, leather and other similar pieces of work, an instrumentality for operating on the work, a feeding member movably mounted adjacent to the operating instrumentality, a plurality of bed rolls for supporting pieces of work, a turret member carrying the bed rolls and movable to present the bed rolls in succession in co-operative relation with respect to the operating instrumentality and the feeding member, each bed roll being yieldingly adjustable to accommodate variations in the thickness of the piece of work between it and the operating instrumentality, and means associated with each bed roll for automatically adjusting the feeding member with respect to the bed roll as the latter moves in accom-

modating itself to said variations in the work.

22. In a machine for operating upon hides, skins, leather and other similar pieces of work, an instrumentality for operating on the work, a movably mounted feeding member adjacent to the operating instrumentality, a plurality of bed rolls for supporting pieces of work, means for moving the bed rolls in succession into co-operative relation with respect to the operating instrumentality and the feeding member, and means associated with each bed roll for causing movement of the feeding member into proper co-operative relation with respect to the bed roll.

70 23. In a machine for operating upon hides, skins, leather and other similar pieces of work, an instrumentality for operating on the work, a movably mounted feeding member adjacent to the operating instrumentality, a plurality of bed rolls for supporting pieces of work, means for carrying the bed rolls in succession into co-operative relation with respect to the operating instrumentality and the feeding member, and means associated with the carrying means for moving the feeding member into proper co-operative relation with respect to each bed roll in turn.

75 24. In a machine for operating upon hides, skins, leather and other similar pieces of work, an instrumentality for operating on the work, a movably mounted feeding member adjacent to the operating instrumentality, a plurality of bed rolls for supporting pieces of work, a turret member movable intermittently for carrying the bed rolls in succession into co-operative relation with respect to the operating instrumentality and the feeding member, a support for the feeding member, and turret controlled means for locking the support of the feeding member with the latter in co-operative relation to a bed roll at the end 90 of each movement of the turret member.

95 25. In a machine for operating upon hides, skins, leather and other similar pieces of work, an instrumentality for operating on the work, a movably mounted feeding member adjacent to the operating instrumentality, a plurality of bed rolls for supporting pieces of work, a turret member for carrying the bed rolls in succession into co-operative relation with respect to the operating instrumentality and the feeding member, a support for the feeding member, means controlled by each bed roll for moving the feeding member and its support so that the feeding member is brought into proper co-operative relation to the bed roll irrespective of the size of the latter, and turret controlled means for locking the feeding member support in the position to which 100 115 120 125 130

it is moved by the operation of the bed roll controlled means.

26. In a machine for operating upon hides, skins, leather and other similar pieces of work, an instrumentality for operating on the work, a bed roll movable between work receiving and work presenting positions with respect to the operating instrumentality, and means for maintaining the bed roll with a given surface thereof facing upwardly during each movement of the bed roll between work receiving and work presenting positions.

27. In a machine for operating upon hides, skins, leather and other similar pieces of work, an instrumentality for operating on the work, a bed roll, swing arms for moving the bed roll between work receiving and work presenting positions with respect to the operating instrumentality, and means for turning the bed roll in a direction to keep a given surface thereof facing upwardly during swinging movement of the bed roll from work receiving to work presenting position.

28. In a machine for operating on hides, skins, leather and similar pieces of work, an instrumentality for operating on the work, a bed roll movable between work receiving and work presenting positions with respect to the operating instrumentality, means for maintaining the bed roll with a given portion of its surface facing always in the same direction during travel of the bed roll from work receiving to work presenting position, and means for rotating the bed roll while in work presenting relation with respect to the operating instrumentality.

29. In a machine for operating upon hides, skins, leather and other similar pieces of work, an instrumentality for operating on the work, a plurality of bed rolls, a turret member for carrying the bed rolls in succession between work receiving and work presenting positions with respect to the operating instrumentality, and means for maintaining each bed roll with a given surface thereof facing upwardly during movement of the bed roll between work receiving and work presenting positions.

30. In a machine for operating upon hides, skins, leather and other similar pieces of work, an instrumentality for operating on the work, a plurality of bed rolls, a turret member for carrying the bed rolls in succession between work receiving and work presenting positions with respect to the operating instrumentality upon half-turn movements of the turret member, and means for turning each bed roll in a counterclockwise direction, continuously and at the same rate as the rotating turret member would normally reverse the upper and lower surfaces of each bed roll in each half turn of the turret member, in order to maintain a

given surface on each bed roll facing upwardly during movement of that bed roll between work receiving and work presenting positions.

31. In a machine for operating upon hides, skins, leather and other similar pieces of work, an instrumentality for operating on the work, a bed roll movable between work receiving and work presenting positions with respect to the operating instrumentality, and weighted members supported by the bed roll and operative to maintain the latter with a given surface thereon facing upwardly during movement of the bed roll between work receiving and work presenting positions.

32. In a machine for operating upon hides, skins, leather and other similar pieces of work, an instrumentality for operating on the work, a bed roll movable between work receiving and work presenting positions with respect to the operating instrumentality, weighted members loosely mounted at each end of the bed roll, a ratchet wheel associated with each weighted member and fastened to the bed roll, and a ratchet pawl carried by each weighted member to operate on the adjacent ratchet wheel to cause turning of the bed roll during its movement between work receiving and work presenting positions.

33. In a machine for operating upon hides, skins, leather and other similar pieces of work, a bladed cylinder, a feed roll located adjacent to the cylinder, a plurality of bed rolls for carrying pieces of work, means for moving the bed rolls in succession from a work receiving position into co-operative relation with respect to the bladed cylinder and the feed roll, means for mounting the feed roll for movement into and out of co-operative relation with respect to a bed roll in work presenting position with respect to the bladed cylinder, and means for moving the feed roll out of the way of that bed roll during its return to work receiving position.

34. In a machine for operating upon hides, skins, leather and other similar pieces of work, a bladed cylinder, a feed roll located adjacent to the cylinder, a plurality of bed rolls for carrying pieces of work, a turret member rotatable for moving the bed rolls in turn between work receiving and work presenting positions with respect to the bladed cylinder, a pivotal mounting for the feed roll, and means controlled by the turret member for lifting the feed roll out of the circular path of each bed roll as the latter passes away from co-operative relation with respect to the bladed cylinder.

35. In a machine for operating upon hides, skins, leather and other similar pieces of work, a bladed cylinder, a feed roll located adjacent to the cylinder, a plurality

of bed rolls for carrying pieces of work, a 5
turret member for carrying the bed rolls in
turn between work receiving and work pre-
senting positions with respect to the bladed
cylinder, pivoted members for supporting
the feed roll, and a pair of levers located
below the plane of the bladed cylinder and
arranged to be operated by the turret mem-
ber to lift the feed roll as a bed roll is com-
ing into work presenting position with re-
spect to the bladed cylinder so that the piece
of work on the bed roll does not support the
feed roll during upward movement thereof.

36. In a machine for operating upon 15
hides, skins, leather and other similar pieces
of work, a bladed cylinder, a feed roll located
adjacent to the cylinder, a plurality of bed
rolls for carrying pieces of work, a turret
member for carrying the bed rolls 20
successively between work receiving and
work presenting positions with respect to
the bladed cylinder, members for supporting
the feed roll arranged to be operated by
the turret member for lifting the feed roll
25 as a bed roll is coming into work presenting
position with respect to the bladed cylinder
so that the piece of work on the bed roll does
not support the feed roll during upward
movement thereof, and means for automati-
cally adjusting the feed roll with respect to
30 each bed roll irrespective of the size of the
latter.

37. In a machine for operating upon hides,
skins, leather and other similar pieces of 35
work, a bladed cylinder, a feed roll located
adjacent to the cylinder, a plurality of bed
rolls for carrying pieces of work, a turret
member for carrying the bed rolls between
work receiving and work presenting posi-
40 tions with respect to the bladed cylinder,
members for supporting the feed roll ar-
ranged to be operated by the turret member
for lifting the feed roll as a bed roll is com-
ing into work presenting position with
45 respect to the bladed cylinder so that the
piece of work on the bed roll does not sup-
port the feed roll during upward movement
thereof, and means controlled by the turret
member for causing the feed roll to be ad-
50 justed to each bed roll irrespective of the
size of the latter.

38. In a machine for operating upon hides,
skins, leather and other similar pieces of 55
work, a bladed cylinder, a feed roll located
adjacent to the cylinder, a plurality of bed
rolls for carrying pieces of work, a turret
member for carrying the bed rolls between
work receiving and work presenting posi-
60 tions with respect to the bladed cylinder,
members for supporting the feed roll ar-
ranged to be operated by the turret member
for lifting the feed roll as a bed roll is com-
ing into work presenting position with re-
65 spect to the bladed cylinder so that the piece

of work on the bed roll does not support the
feed roll during upward movement thereof,
boxes for mounting the ends of the bed roll
in the turret member, and cam projections on
the boxes for controlling the position of the
feed roll with respect to each bed roll irre-
spective of the size of the latter. 70

39. In a machine for operating upon hides,
skins, leather and other similar pieces of 75
work, a bladed cylinder, a feed roll located
adjacent to the cylinder, a plurality of bed
rolls for carrying pieces of work, a turret
member for carrying the bed rolls between
work receiving and work presenting posi-
80 tions with respect to the bladed cylinder,
pivoted members for supporting the feed
roll, a pair of levers located below the plane
of the bladed cylinder and arranged to be
operated by the turret member for lifting the
85 feed roll as a bed roll is coming into work
presenting position with respect to the
bladed cylinder so that the piece of work on
the bed roll does not support the feed roll
during upward movement thereof, boxes for
90 mounting the ends of the bed roll in the tur-
ret member, and cam projections on the
boxes for controlling the position of the feed
roll with respect to each bed roll irrespec-
tive of the size of the latter.

40. In a machine for operating upon hides,
skins, leather, and other similar pieces of
work, an instrumentality for operating on
the work, a bed roll for presenting a piece of
work to the operating instrumentality, a feed
roll for cooperation with the bed roll in
100 feeding the work past the operating instru-
mentality, and means under the control of
the operator for changing the speed of the
feed roll without affecting the speed of the
operating instrumentality. 105

41. In a machine for operating upon hides,
skins, leather and other similar pieces of
work, a bladed cylinder, a bed roll for pre-
senting a piece of work to the cylinder, a
feed roll for co-operation with the bed roll
in feeding the work past the cylinder, means
110 for driving the cylinder, means for driving
the feed roll positively and independently
of the driving means for the bladed cylinder,
said feed roll driving means comprising a
set of gears of different sizes and means
115 under the control of the operator for selec-
tively introducing the gears into the driving
means for the feed roll.

42. In a machine for operating upon hides,
skins, leather and other similar pieces of
work, an instrumentality for operating on
the work, a bed roll for presenting a piece of
work to the operating instrumentality, a
feed roll for co-operation with the bed roll
in feeding the work past the operating instru-
mentality, a set of gears of different sizes,
120 a pinion constituting part of the feed
roll driving means, and means under the
control of the operator for shifting the
125

- pinion to engage selectively with the gears to vary the speed of the feed roll.
43. In a machine for operating upon hides, skins, leather and other similar pieces of work, an instrumentality for operating on the work, a plurality of bed rolls for carrying pieces of work, a turret member for carrying the bed rolls in succession into co-operative relation with respect to the operating instrumentality, boxes for supporting the ends of each bed roll in the turret member, said boxes being adjustable in the turret member to position each bed roll in predetermined relation to the operating instrumentality, and spring means for yieldingly backing each bed roll so that it may yield away from the operating instrumentality to accommodate variations in the thickness of the work, each said spring means being adjustable in tension independently of the adjustment of its associated box.
44. In a machine for operating upon hides, skins, leather and other similar pieces of work, an instrumentality for operating on the work, a plurality of bed rolls for carrying pieces of work, a turret member for carrying the bed rolls in succession into co-operative relation with respect to the operating instrumentality, boxes for supporting the ends of each bed roll in the turret member, said boxes being adjustable in the turret member to position each bed roll in predetermined relation to the operating instrumentality, a plate associated with each box and adjustable with respect thereto, and a spring means between each plate and box and arranged to be adjusted as to tension by the plate.
45. In a machine for operating on hides, skins, leather and similar pieces of work, a bladed cylinder for operating on pieces of work, a pair of bed rolls each adapted to receive a piece of work looped thereover while in work receiving position and arranged to be alternately moved into co-operative relation with respect to the bladed cylinder, and means for mounting each bed roll for rotation while it is supporting the work against the thrust of the cylinder.
46. In a machine for operating upon hides, skins, leather and other similar pieces of work, an instrumentality for operating on the work, and a plurality of bed rolls for supporting pieces of work and movable in succession from work receiving position to present the pieces of work in turn to the operating instrumentality and to co-operate therewith in the treatment of the work, each bed roll when in work receiving position being stationary and spaced a considerable distance from the operating instrumentality, and means for rotating each bed roll while it is supporting the work against the thrust of the operating instrumentality.
47. In a machine for operating upon

hides, skins, leather and other similar pieces of work, a cylinder for operating on the work, means comprising a feed roll for feeding the work past the cylinder, a turret member rotatable about an axis parallel to the cylinder, and a plurality of bed rolls carried by the turret member and movable in succession from work receiving position to present the pieces of work in turn to the cylinder, each bed roll when in work receiving position being spaced a considerable distance from the feed roll and the cylinder.

In testimony whereof I have signed my name to this specification.
